MUFF-CONVERTIBLE CUFF

Stephen J. Kennedy, Needham Heights, Mass., assignor to the United States of America as represented by the Secretary of the Army

Application August 15, 1957, Serial No. 678,460

3 Claims. (Cl. 2—270)

(Granted under Title 35, U.S. Code (1952), sec. 266)

The invention described herein, if patented, may be 15 manufactured and used by or for the Government for governmental purposes, without the payment to me of any royalty thereon.

This invention relates to wearing apparel for use in cold climates, and particularly to the sleeves of a parka or overcoat.

An object of the invention consists in providing the sleeves of a coat or the like with a heat-insulated cuff which may be positioned just above the wrist in conventional position, or may be drawn down over the hand to form a muff section.

Another object of the invention resides in the addition of a "patch" or the like of friction material at a suitable point on the exterior of the cuff to facilitate the extension or retraction of the cuff section when it is desired to either use it as a muff or to uncover the hand to permit a high degree of dexterity, respectively.

A still further object of the invention consists in providing coverings of sleeve material on the interior and exterior of the sleeve adjacent the upper end of the cuff for the purpose of reducing friction as the muff is slid upwardly along the sleeve to inoperative position.

Other objects and advantages of the invention will be apparent from the following description taken in connection with the accompanying drawings, in which,

Figure 1 is a perspective view of an outer garment with the novel sleeve attachment incorporated therein;

Figure 2 is an enlarged fragmentary elevational view of one of the sleeves with the slidable cuff attached thereto;

Figure 3 is an enlarged sectional view taken on line 3—3 of Figure 2;

Figure 4 is an enlarged horizontal sectional view taken on line 4—4 of Figure 2; and

Figure 5 is a greatly enlarged sectional view of the seams joining the cuff to the sleeve, etc.

Referring to the drawing in greater detail and by reference numerals, the body of the garment, which may be in the form of a parka or other type of outer garment, is indicated by the numeral 10. The main portion of the sleeves is indicated by the numeral 11, and the numeral 12 indicates a hood.

In the embodiment of the invention shown herein, the main portion of the sleeve will terminate at the point 13 a substantial distance above the wrist of the wearer approximating the elbow, and the combined cuff and muff section 14 is attached to the lower end of the sleeve 11 in a manner to be later described. This section 14 is in the form of a closed annular pocket 15 filled with suitable heat insulating material 16.

The length of the combined cuff and muff is preferably such that when attached to the sleeve portion 11 its lower end will extend slightly below the finger tips of the wearer's hand, and the insulating material 16 may be confined against undue shifting by means of vertical lines of stitching 17 which extend from the top of the cuff to a point adjacent to the bottom thereof. The cuff

2

terminates at its lower end in a continuous bead 18 formed by a circular line of stitching 19.

In order to facilitate the movement of the muff 14 from the active position shown in Figures 2 and 3 and 5 at the left of Figure 1 to the inoperative or cuff position shown at the right of Figure 1, it is highly desirable that the connection between the parts be such as to reduce friction between the parts to a minimum. To this end, an outer band of sleeve material 20 has its upper edge attached to the sleeve material 11 by a line of stitching 21 spaced a distance from the lower end of the sleeve material approximating one-half the length of the element 14, and its lower end attached to the upper end of element 14 by a line of stitching 22. Also, the lower edge of the sleeve material 11 is attached to an inner band of sleeve material 23 by a line of stitching 24, while the lower edge of the band which has a vertical dimension approximating one-half the length of the element 14 is attached to the inner face thereof by a line of stitching 25.

It will be understood, of course, that in climates where the particular article of wearing apparel would be most serviceable, the hands of the wearer would normally be incased by the muff 14 as shown at the left of Figure 1, and therefore would be incapable of sliding the muff upwardly into the position shown at the right of Figure 1 when necessary to expose the hands for manipulative purposes. Accordingly, the faces of the muffs 14 which are adjacent the body of the wearer may each 25 have secured thereto a patch 26 of any flexible rough-surfaced material. With this arrangement, it will be obvious that by pressing the friction material against the wearer's body and simultaneously moving the arm downwardly toward the knee the muff may be pushed upwardly from the operative position shown at the left of Figure 1 to the position simulating a cuff at the right of Figure 1, thereby freeing the hand for manipulative purposes. This element 26 will also serve the same purpose in returning the cuff 14 to its operative position.

40 This sliding movement of the element 14 from what may be termed the muff position to the cuff position is facilitated by the incorporation in the sleeve structure of one or both of the bands 20 and 23 of sleeve material.

45 These bands which, respectively, secure the upper edge of the element 14 to the sleeve material at a point spaced from its lower edge and the mid-portion of element 14 to the lower edge of the sleeve material 11, serve to eliminate or greatly reduce friction between the moving parts when the element is moved from operative to inoperative position, or vice versa. It should be noted also that the outer band 20 on the exterior of the sleeve will serve to prevent the accumulation of snow, 50 ice, or water in the area between the muff and the sleeve when the muff is pushed back into the position of a cuff since the crinkling of this material precludes the formation of a pocket which would retain such elements.

55 In accordance with the patent laws, I have described what I now consider to be the preferred form of the invention, but inasmuch as various minor changes may be made in structural details without departing from the spirit of the invention, it is intended that all such changes be included within the scope of the appended claims.

I claim:

60 1. In a coat or the like having a sleeve, a band of sleeve material having its upper edge secured to the outer face of the sleeve, a second band of sleeve material having its upper edge secured to the inner face of the sleeve, and an open-ended muff section having its upper edge secured to the lower edge of the first-mentioned band and its inner mid-portion secured to the lower edge of the second-mentioned band.

65 2. In a coat or the like having a sleeve, a band of

sleazy material having its upper edge secured to the outer face of the sleeve, a second band of sleazy material having its upper edge secured to the inner face of the sleeve, and an open-ended muff section having its upper edge secured to the lower edge of the first-mentioned band, its inner mid-portion secured to the lower edge of the second-mentioned band, and friction material attached to the muff section on the side facing the body of the coat.

3. A coat or the like having a sleeve terminating adjacent the wearer's elbow, bands of sleazy material attached to the inner and outer faces of the sleeve, one of said bands being attached to the end of the sleeve

and the other band being attached at a point above the end of the sleeve, and an open-ended muff section, one of said bands having its lower edge attached to the upper edge of the muff section and the other band having its lower edge attached to the mid-portion of the muff section.
